US00D792347S

(12) **United States Design Patent** (10) **Patent No.:** **US D792,347 S**
(45) **Date of Patent:** **** Jul. 18, 2017**

(54) **ELECTRICAL CONNECTOR**

(71) Applicant: **The Wiremold Company**, West Hartford, CT (US)

(72) Inventors: **Daron Callahan**, New Britain, CT (US); **Peter M. Schneider**, North Richland Hills, TX (US); **David Singer**, Austin, TX (US); **Kenneth J. Buras**, Spring, TX (US)

(73) Assignee: **The Wiremold Company**, West Hartford, CT (US)

(**) Term: **15 Years**

(21) Appl. No.: **29/564,149**

(22) Filed: **May 11, 2016**

Related U.S. Application Data

(63) Continuation of application No. 14/180,930, filed on Feb. 14, 2014, which is a continuation of application No. 13/247,573, filed on Sep. 28, 2011, now Pat. No. 8,651,460.

(57) **CLAIM**

The ornamental design for an electrical connector, as shown and described.

DESCRIPTION

FIG. 1 is a front, top, right side perspective view of a first embodiment of the electrical connector, showing our new design;

FIG. 2 is a front view thereof;

FIG. 3 is a right side view thereof (left side view being a mirror image thereof);

FIG. 4 is a top view thereof;

FIG. 5 is a front, top, right side perspective view of a second embodiment of the electrical connector, showing our new design;

FIG. 6 is a front view thereof;

FIG. 7 is a right side view thereof (left side view being a mirror image thereof); and,

FIG. 8 is a top view thereof.

In the drawings, the broken lines are for the purpose of illustrating environment only and form no part of the claimed design.

1 Claim, 6 Drawing Sheets
